UNITED STATES PATENT OFFICE.

HAROLD G. WARR, OF PARK RIDGE, ILLINOIS, ASSIGNOR TO THE P & M COMPANY, OF CHICAGO, ILLINOIS, A CORPORATION OF ILLINOIS.

GUARD-RAIL CLAMP.

1,415,742.

Specification of Letters Patent.

Patented May 9, 1922.

Application filed September 4, 1920. Serial No. 408,234.

To all whom it may concern:

Be it known that I, HAROLD G. WARR, a citizen of the United States, residing at Park Ridge, in the county of Cook and State 5 of Illinois, have invented certain new and useful Improvements in Guard-Rail Clamps, of which the following is a specification.

This invention relates to guard rail clamps.

10 One of the objects of the invention is to provide a guard rail clamp of improved construction which is strong, durable, and relatively inexpensive in cost of manufacture.

Another object is to provide a device of 15 this character which may be more readily adjusted to compensate for wear and to permit the readjustment of various track elements which get out of adjustment and alignment through use.

20 A further object is to provide a guard rail clamp which will permit the guard rail to rise responsively to the movement of the running rail as a train passes over it, so as to prevent breakage and distortion resulting 25 from the rigid anchoring of the guard rail to the tie.

A still further object is to provide a guard rail clamp which will not transmit to the running rail the shocks and blows received 30 by the guard rail from the passage of a train and in which an improved anchorage is provided for transmitting such shocks and blows directly to the ties.

The invention consists in the novel constructions, combinations and devices herein-after described and claimed, for carrying out the above stated objects and such other objects as will appear from the following description.

40 The drawings illustrate certain preferred embodiments of the invention:

Figure 1 is a vertical cross section through a guard and running rail showing the guard rail clamp in elevation.

45 Figure 2 is a plan view of the same.

Figure 3 is a perspective showing the base of the device and the guard rail abutment.

Figure 4 is a detail section taken along the line 4-4 of Fig. 2, showing the manner

of anchoring the guard rail abutment to the 50 base plate.

Figure 5 is a view similar to Figure 1 illustrating a modified form of adjustable chock.

Figure 6 is an elevation similar to that 55 shown in Figure 1 illustrating a modified form of side rail clamp, and

Figure 7 is a plan view of the construction shown in Fig. 6.

Like characters of reference designate like 60 parts in the several figures of the drawings.

Referring to the drawings, the main or running rail 1 and the guard rail 2 rest directly upon the base plate 3, which takes the place of the usual tie plate. The base plate 65 is preferably of rolled steel having spike holes 4 therein and is preferably provided with struck up abutments or lugs 5 adapted to engage the outer rail base of the running rail. The guard rail brace comprises an 70 abutment 6 and an adjustable block 7 adapted to engage the guard rail. The abutment 6 is preferably of cast metal and is secured to the base plate 3 by casting the same through suitable openings 11 in the plate. 75 For this purpose the plate 3 is preferably offset, as shown at 8, and metal is cast under the offset portion in the form of a plate 9 which rigidly anchors the abutment 6 in place and provides also a flat bottom for the 80 plate 3. In order to reduce weight the abutment 6 is preferably cored out, as shown at 10, during the casting operation.

The face 12 of the abutment 6 is formed at an angle to the face 13 of the block 7 and 85 provided with a correspondingly inclined groove or guideway 14. The block 7 is provided with a correspondingly inclined face 15 and a tongue or rib 16 adapted to fit and slide within the groove 14. A plurality of 90 adjusting notches 17 are formed in the rib 16. A pair of perforated lugs 18 are formed on the abutment 6 adjacent the groove 14 through which a pin 19 is adapted to pass in order to engage one of the adjusting 95 notches, so as to retain the block 7 in adjusted position. If desired, the arrangement of the rib and groove may be reversed by

providing the block with a groove and the abutment with a rib. Any other suitable means for obtaining relative adjustment may be employed. The face 13 of the block 7 is shaped to conform to the upper portion of the web of a rail, as shown more clearly in Fig. 1. A space 20 is provided below the lower face of the block and abutment so as to permit the flange of the guard rail to rise, if necessary.

The rails are spaced apart and wedged against opposing abutments 5 and 6 by the adjusting chock 21. The chock 21 comprises a pair of blocks 22 and 23, whose adjacent faces are inclined relative to the webs of the rails so that the effective width of the chock may be varied by sliding one block on the other. The adjacent faces of the blocks 22 and 23 are notched or serrated, as shown at 24, to provide cooperating surfaces which will prevent relative movement between the blocks when they are placed in adjusted position. The blocks are also provided with a horizontal tongue 25 and groove 26, respectively, so as to prevent relative vertical displacement. One of the blocks, in this case the block 22, is provided with a downwardly projecting lug 27 adapted to extend into the slot or recess 28 in the base 3 so as to prevent longitudinal displacement of the chock with respect to the base.

Operation: The rail base may be placed in position, if necessary, without removing the rail. The base 3 is spiked in a position, 35 determined by the running rail 1 over the flange of which the lugs 5 fit. The block 7 is adjusted on the inclined face 12 of the abutment, so as to adjust the distance between the outside face of the guard rail and 40 the inside face of the opposite running rail at the proper gauge to prevent the opposite flanges of the wheels of a train from striking the frog of the switch. Inasmuch as this adjustment is the controlling adjustment of the guard rail it is desirable to provide a guard rail brace which may be easily adjusted. If the inner face of the guard rail becomes worn, or the track becomes out of alignment through usage, the guard rail may 45 be again adjusted by sliding the block 7 over the inclined base 12 and locking the same in position by the pin 19. The chock 21 serves to hold the rails in position.

The block 7 is preferably molded and the 55 notches 17 are preferably formed in the rib 16 during the molding operation. No machining of the adjusting elements of the guard rail brace is necessary. This cheapens the construction.

60 The provision of the space 20 below the lower face of the guard rail brace permits the guard rail to rise and thus prevent distortion and the eventual breaking of the guard rail brace by the passage of trains over 65 the rails. The passage of a train over a

track causes the running rail to rise slightly in front of the leading wheels. The rising of the running rail tends to lift the guard rail and accordingly it is desirable, in order to avoid damage, to permit the guard rail 70 to rise slightly instead of anchoring the same firmly in position.

In Figure 5 I have shown a modified construction of chock. The chock 29 is provided with a lug 30 adapted to fit within a corresponding slot or recess in the web of the guard rail 31. This construction takes the place of the lug 27 in the form shown in Figure 1 and serves to prevent displacement of the chock. In other respects the chock 75 29 is like that shown in Figure 1.

In Figs. 6 and 7 I have shown a modified form of rail brace. The guard rail brace is adapted to be positioned between the ties. It comprises a plate 32, preferably of rolled 85 steel, which extends across adjacent ties. The yoke 33 is preferably formed separately by casting and secured to the plate 32 by a plurality of rivets 34 which pass through suitable attaching lugs 35 and bracing ribs 90 36. If desired, the yoke 33 may be secured to the plate 32 by casting the same through openings in the plate in the manner described in connection with the form shown in Figs. 1 to 4. Under certain conditions it 95 may even be desirable to cast the yoke and plate in one piece out of cast steel. The manner of making the yoke and plate and of connecting the same together is usually determined by the costs of the various materials and of manufacture.

The yoke 33 terminates in a hook 37 adapted to extend over the base flange of the running rail 38. The guard rail abutment 39 is preferably cast hollow and is similar in construction to 100 that shown in Figs. 1 to 3 inclusive. The guard rail adjusting block 40 is likewise similar in construction to that shown in Figs. 1 to 3 inclusive. The adjustable chock 41 is provided with a pair of spaced downwardly extending lugs 42 adapted to straddle the yoke 33 to prevent displacement of the chock. In other respects it is similar to that shown in Figs. 1 and 2.

The shocks and blows received by the 115 guard rail from the passage of a train are received by the plate 32 through the guard rail brace and transmitted to the two adjacent ties. This distributes the stress and at the same time increases the resistance to 120 displacement of the rail or ties. Substantially none of this stress is transmitted through the yoke to the running rail.

The operation of the modified forms of construction shown in Figs. 5, 6 and 7 is 125 similar to that previously described in connection with Figs. 1 to 4 inclusive and further detailed description is not necessary.

I claim:

1. A guard rail clamp of the type de- 130

scribed comprising in combination a base, a guard rail brace comprising a member rigidly secured to said base and a block adapted to engage a guard rail, said member and block having cooperating engaging faces inclined to the rail engaging face of said block, said block engaging only the upper portion of a guard rail and leaving a space below said block and member to permit the free upward movement of the guard rail.

2. A guard rail clamp of the type described comprising an abutment rigidly secured to said base, and a block adapted to engage a guard rail, said abutment and block provided with cooperating faces inclined to the rail engaging face of said block, said inclined face of said block being provided with a rib having a plurality of adjusting notches and said face of said abutment provided with a groove adapted to receive said rib and a locking key on said abutment for engaging said notches to hold said block in adjusted position.

3. A guard rail clamp comprising in combination a base adapted to receive a guard rail and a running rail, an abutment rigidly secured to said base, and a block adapted to engage a guard rail, said abutment and block providing a space below the same for permitting the guard rail to rise, provided with cooperating faces inclined to the rail engaging face of said block, said inclined face of said block being provided with a rib having a plurality of adjusting notches and said face of said abutment provided with a groove adapted to receive said rib and locking means for engaging said notches to hold said block in adjusted position.

4. A guard rail clamp of the type described comprising an abutment rigidly secured to said base, and a block adapted to engage a guard rail, said abutment and block provided with cooperating faces inclined to the rail engaging face of said block, said inclined face of said block being provided with a rib having a plurality of adjusting notches and said face of said abutment provided with a groove adapted to receive said rib and locking means comprising a pair of spaced perforated lugs and a pin slidable therethrough for engaging said notches to hold said block in adjusted position and an adjustable chock for adjustably spacing the guard and running rails.

5. In a guard rail clamp the combination of a base adapted to receive a guard rail and a running rail, an abutment rigidly secured to said base and adapted to engage the upper portion of a guard rail and providing a space below to permit the guard rail to rise, and an abutment on said base for engaging the outer flange of said running rail.

6. In a guard rail clamp the combination of a base and a guard rail and a running

rail, of an abutment rigidly secured to said base and adapted to engage the upper portion of said guard rail and providing a space below to permit said guard rail to rise, an abutment on said base for engaging the outer flange of said running rail and an adjustable chock between said rails.

7. In a guard rail clamp the combination with a guard rail and a running rail, of a plate on which said rails rest, an abutment rigidly secured to said plate and engaging said guard rail, lugs struck up from said plate for engaging the outer flange of said running rail, and an adjustable chock between said rails having a lug thereon extending into an opening in the web of said guard rail.

8. In a guard rail clamp, the combination with a guard rail and a running rail, of a plate adapted to be secured to a tie, said plate provided with struck up lugs adapted to engage the base of said running rail, an abutment rigidly secured to said plate adapted to permit vertical movement of the guard rail and provided with an adjustable block for engaging said guard rail to prevent lateral movement thereof, and an adjustable chock between said rails.

9. A guard rail clamp, comprising in combination a rolled metal plate provided with openings, and adapted to be secured to a tie, a guard rail brace comprising a hollow abutment cast to said plate and anchored thereto through said openings, an adjustable block slidable on said abutment and adapted to engage a guard rail.

10. A guard rail clamp, comprising in combination a rolled metal plate provided with openings, and adapted to be secured to a tie, a guard rail brace comprising a hollow abutment cast to said plate and anchored thereto through said openings, an adjustable block slidable on said abutment and adapted to engage a guard rail, said plate provided with struck up lugs for engaging the face of an adjacent running rail.

11. A guard rail clamp, comprising in combination a rolled metal plate provided with openings, and adapted to be secured to a tie, a guard rail brace comprising a hollow abutment cast to said plate and anchored thereto through said openings, a block adapted to engage a guard rail, said abutment and block having cooperating engaging faces inclined to the outer face of said block, means for adjusting said block relatively to said abutment, and means on said plate for engaging a running rail.

12. A guard rail clamp of the type described comprising an abutment rigidly secured to a base, and a block adapted to engage a guard rail, said abutment and block provided with cooperating faces inclined to the rail engaging face of said block, said inclined face of said block being provided with

a rib having a plurality of adjusting notches on its vertical edge, and said face of said abutment provided with a groove adapted to receive said rib, and means on said abutment adapted to engage in one of said notches for holding said block in adjusted position.

13. A guard rail clamp, comprising in com-

bination a rolled metal plate provided with openings, and adapted to be secured to a 10 tie, a guard rail brace comprising an abutment cast to said plate, and anchored thereto through said openings, an adjustable block slidable on said abutment and adapted to engage a guard rail.

HAROLD G. WARR.
